UNITED STATES PATENT OFFICE.

ABRAHAM L. FOX, OF DANVILLE, ILLINOIS.

DESIGN FOR A PUMP-BODY.

SPECIFICATION forming part of Design No. 33,421, dated October 23, 1900.

Application filed September 15, 1900. Serial No. 30,183. Term of patent 3½ years.

To all whom it may concern:

Be it known that I, ABRAHAM L. FOX, a citizen of the United States, residing at Danville, in the county of Vermilion and State of Illinois, have invented and produced a new and original Design for Pump-Bodies, of which the following is a specification, reference being had to the accompanying drawings, forming part thereof.

- 10 Figure 1 of the drawings represents a perspective view of my pump-body design. Fig. 2 is a central vertical section of the same. Fig. 3 is a transverse section on the line 3 3 of Fig. 1.
- 15 1 represents the cylinder. 2 is an opening in the side thereof.
- 3 is the enlarged disk-shaped base, provided at intervals around its circumference with openings 4.

5 represents the downwardly-projecting 20 bevel-shaped edge of the base.

My design is characterized as a body having at its base a circular-base enlargement provided with perforations, the interior of the pump communicating with the recessed 25 base.

Having described my design, what I claim as new, and desire to secure by Letters Patent of the United States, is—

The design for a pump-body, substantially 30 as shown and described.

In testimony whereof I have affixed my signature in the presence of two witnesses.

ABRAHAM L. FOX.

Witnesses:

GEO. C. TODD,
L. M. LOCKE.
